Primary Examiner — Marie D. Fast Horse(74) *Attorney, Agent, or Firm* — Altera Law Group, LLC(57) **CLAIM**

The ornamental design for a speaker phone, as shown and described.

DESCRIPTION

FIG. 1 is a perspective view of a speaker phone.

FIG. 2 is another perspective view thereof.

FIG. 3 is a front view thereof.

FIG. 4 is a back view thereof.

FIG. 5 is a side view thereof.

FIG. 6 is the other side view thereof.

FIG. 7 is a top view thereof; and,

FIG. 8 is a bottom view thereof.

The features shown in broken lines depict portions of the speaker phone that form no part of the claimed design.

1 Claim, 6 Drawing Sheets(56)
